(57) **CLAIM**

The ornamental design for a wing shroud, as shown and described.

DESCRIPTION

FIG. 1 is a perspective view of a wing shroud showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the wing shroud which form no part of the claimed design.

The dot-dash broken lines depict boundaries which form no part of the claimed design.

1 Claim, 7 Drawing Sheets See application file for complete search history.
